GAME BOARD

Application filed March 22, 1929. Serial No. 349,132.

Our invention relates to amusement devices and has for its object the provision of a game including a game board having a hard highly polished surface preferably of glass, and 5 movable pieces or "nine pins" and adapted to be knocked over by a top spun upon the board.

Heretofore it has been the practice to have the game board so constructed that the front 10 end is elevated, that is the end from which the top is spun.

The disadvantage of a game board so constructed we find resides in the fact that when the top is spun, instead of traveling with 15 distance towards the movable pieces or nine pins as intended, the top generally remains on the spot on which the top was spun.

A feature of our invention resides in the construction and particularly the way the 20 game board is tilted so as to give the game board a slight lopsided slant.

Another feature of our invention is the method of causing the top always to travel 25 forward toward the movable pieces or nine pins.

Another feature of our invention is the provision of a pocket in the game board for the purpose of storing the movable pieces or nine pins and top when they are not in use.

30 Another feature of our invention is the provision of markers for the purpose of properly placing the movable pieces or nine pins.

We attain these objects in the following described manner, as illustrated in the accompanying drawing, in which similar numerals 35 appear for similar parts throughout the several views.

Fig. 1 is a perspective view showing the 40 game board with parts cut away for the sake of clearness.

Fig. 2 is a top view.

Fig. 3 illustrates the spinning top.

Referring more particularly to the drawings, we have illustrated our game board as 45 comprising a rectangular or oblong box-like structure, comprising a wood bottom 1, a glass surface 2, a leg 3 which is longer than any of the other legs, a leg 4 which is next in height, a leg 5 next in height, and a leg 6, the

shortest, and sides and end pieces 9, assembled as shown.

In the rear end of our game board we have provided a pocket or compartment 13, comprising walls 10, 11 and bottom 12, and end 55 pieces. We have provided this pocket so that when any of the movable pieces or nine pins are knocked over or not in use they may be accommodated therein.

The game further includes a top 7, as illustrated in Fig. 3, and is specially designed with a blunt point 14.

We have provided a set of markers, nine in all, and positioned to one side of the game board as illustrated in Figs. 1 and 2, so as 65 to properly facilitate the correct placing of the movable pieces or nine pins designated 8.

In playing the game it is of course obvious that the game board should be placed upon a table or other rigid surface; the movable 70 pieces or nine pins are then placed in position; the player takes the top 7 and gives it a twirl with the hand from the starting position or line 15. The top, after thus being spun, will travel in a forward direction 75 towards and contact with one or more of the movable pieces or nine pins 8, knocking or bowling over any or all of them.

The reason for the top traveling in the proper direction is one of the features of 80 our invention and we believe it is due to two causes: first, the peculiar or lopsided slant of the game board obtained by our particular construction, in that each of the legs is of a different height, the front end having the 85 two highest legs, 3 and 5, and the rear or lower end the two shortest legs, 4 and 6; second, the design of the top itself, which we desire to point out is designed to have a blunt point 14.

From the foregoing description and a study 90 of the drawing, it will be apparent that we have provided a game board of novel and simple construction, which may be played with any number of "nine pins" or movable pieces.

Having thus described our invention, we 95 claim:

1. A game board comprising a base member side and end retaining walls, a rear end compartment, a set of markers on surface of 100

said board, a surface member, four legs each of different length supporting base member.

2. The combination of a game board comprising a base member, side and end retaining walls, a rear end compartment, a set of markers on the board, a set of pins, a base member, four leg members supporting said board, each member of different length, and a blunt point top for use on said board.

5 10 Signed at Brooklyn, in the county of Queens and State of New York, this twentieth day of March, A. D. 1929.

LORENZ SCHMITT.
BALTHY REICHOLD.
